UNITED STATES PATENT OFFICE.

HAROLD J. CUSACK, OF OAK PARK, ILLINOIS, ASSIGNOR TO THE THOMAS CUSACK COMPANY, A CORPORATION OF NEW JERSEY.

ADVERTISING DEVICE.

1,140,446.

Specification of Letters Patent. Patented May 25, 1915.

Application filed July 9, 1913. Serial No. 778,044.

To all whom it may concern:

Be it known that I, HAROLD J. CUSACK, a citizen of the United States, and a resident of Oak Park, in the county of Cook and State of Illinois, have invented certain new and useful Improvements in Advertising Devices; and I do hereby declare that the following is a full, clear, and exact description thereof, reference being had to the accompanying drawings, and to the letters of reference marked thereon, which form a part of this specification.

This invention relates to improvements in signs or advertising devices and consists of the matters hereinafter described and more particularly pointed out in the appended claim.

The object of the invention is to provide a sign or other advertising device in which the color scheme of the representation depicted upon the sign is constantly variegated by means of bands or sections of colored light which are caused to apparently travel the length of the sign board in an endless procession, thus attracting attention to the sign board and the representation depicted thereon.

In the drawings,—Figure 1. illustrates a vertical section through a sign board made in accordance with my invention. Fig. 2. is an enlarged detail section through the illuminating device which will be more particularly referred to as I proceed with my specification. Fig. 3. is a diagrammatic view illustrating the arrangement of the illuminating lamps and the switch or flasher mechanism therefor.

Referring now to that embodiment of my invention illustrated in the drawings, 10 indicates a placard or sign board, preferably made of sheet metal and supported upon the usual upright members 11, which are braced and held erect by inclined brace bars 12. 13 indicates a plurality of vertically spaced, 45 longitudinally extending horizontal members to which the sign board is attached and which rigidly connect the upright members 11—11 together. There is located in front of the signboard and approximately on a 50 level with the upper edge thereof an inverted trough-like reflector 14, containing a plurality of incandescent lamps 15. Said reflector is supported from the sign structure by means of angle bars 16 which extend back 55 of the sign board a short distance and are

bent downwardly and forwardly and attached to one of the horizontal members 13 on the back of the sign board. The reflector 14 consists of a sheet metal shell having a top wall 17, front and rear walls 18 and 19 and end walls 14^a—14^a. The said front and rear walls are flared outwardly as indicated at 18^a and 19^a, the flared portion 19^a extending below the portion 18^a, so as to throw the light of the lamps 15 upon the signboard. 60 65

20 indicates a lamp supporting plate located a short distance below and parallel with the top wall 17. The plate 20 extends the full length of the reflector and is fixed to the front and rear walls 18 and 19 at its 70 lateral edges thus forming a water-tight compartment to contain the body portions of electric lamp sockets 21, which are attached to the plate 20 in a well known manner. 75

The lamps 15 are arranged in two rows upon the member 20, the lamps of one row being located in staggered relation with the lamps of the other row. This manner of placing the lamps is advantageous in that 80 the rays of the outer row of lamps will not be interfered with or have to penetrate the lamps in the inner row.

In carrying out the scheme of the color illumination, I provide colored bulbs, for 85 instance red, white, yellow and blue and prefer to arrange them so that in one row, red and white lights 24 and 25 will be alternated and in the other row yellow and blue lights 26 and 27 will be alternated (see 90 Fig. 3).

In wiring the lamp, it is preferable to connect one terminal of each lamp with a main 28, in this instance the negative main. 29 indicates the other main (the positive main 95 in this instance), which is connected to a motor driven rotative switch member 30 by means of brushes 31.

35, 36, 37, 38 indicate sets of spring fingers secured to an insulating bar 39. Each 100 finger of each set of said fingers is connected to the other terminal of one of the lamps of one color by means of wires 35^a, 36^a, 37^a, and 38^a. The switch or flasher 30 is provided with spiral shaped contact blades 39^a, 105 with which the spring fingers 35, 36, 37 and 38 are adapted to co-act. By reason of the spiral blades, the spring fingers act to close the circuits for the several lamps of the same color at the time spaced intervals and 110

the spiral blades for the several sets of lamps of different color are arranged at angles to each other so that the contacts for the other color of lamps are closed at successive time intervals intermediate the time intervals of the first named color, with the result that there appears to travel across the face of the sign a plurality of bands of different color. The blades are in advance of one another throughout the flasher, consequently one of the fingers of each set 35, 36, 37 and 38 are always in contact. For instance, when the third finger of the set 35 is in contact with the blade of the flasher, the third red light on the board is then lighted. Just as the blade moves out of contact with the said finger, the fourth finger of the set is in contact with the brush, causing the fourth red lamp to be lighted and when the blade leaves the fourth finger, the first finger is ready for engagement with the blades. The arrangement of the flasher mechanism is such that when the first red light goes out the yellow lamp is lighted, and so on across the board presenting to the eye of the observer the appearance of an endless procession of colors across the board.

The switch member 30 and its driving motor are inclosed in a housing 40, located on the back face of the sign. This housing pro-

tects the switch member 30 and its driving motor from the elements of the weather and from tampering by unauthorized persons.

I claim as my invention:

An advertising device comprising an elongated placard, upon which a representation is depicted, an inverted trough-like reflector arranged in front of and on an approximate level with the upper edge of said placard, a plurality of electric lamps having bulbs of different colors, arranged in longitudinal rows in said reflector, the lamps in one row being staggered relative to the lamps in the adjacent row, each row of lamps having lamps of several colors arranged in succession, the light rays of all of said lamps being reflected upon the representation depicted upon said placard by said reflector, a switch device in circuit with said lamps adapted to control the on and off period of said lamps in succession, to cause bands of light of different color to appear in succession over the length of said placard.

In testimony that I claim the foregoing as my invention I affix my signature in the presence of two witnesses, this 10th day of June A. D. 1913.

HAROLD J. CUSACK.
